PRESSURE TYPE CONTAINER

Erich W. Gronemeyer, Pompton Plains, N. J., assignor to Owens-Illinois Glass Company, a corporation of Ohio

Application November 5, 1952, Serial No. 318,868

5 Claims. (Cl. 222—394)

1

The present invention relates to improvements in pressure type containers and more particularly to a valved dispensing head for such containers.

An object of my invention is the provision of a novel and simple structure which insures against accidental opening of the discharge control valve during shipment, or otherwise. To this end my invention consists in providing a spring closed valve and a valve actuator which is movable from one position wherein it cannot be accidentally or deliberately operated to open the valve, to another position in which it can be moved bodily to effect opening of said valve.

Other objects will be in part apparent and in part pointed out hereinafter.

In the drawings:

Fig. 1 is a fragmentary side elevational view showing my dispensing head attached to a pressure type container;

Fig. 2 is a plan view;

Fig. 3 is a vertical sectional view of the dispensing head and valve, the latter being closed and the actuator being in locked position;

Fig. 4 is a view similar to Fig. 2, but shows the actuator opening the valve; and

Fig. 5 is a sectional view taken along the line 5—5 of Fig. 3, with actuator in operating position.

According to my invention the dispensing head is attached to an end wall 10 of a pressure type container 11 such as are used in dispensing shaving cream, etc., said wall having an annular bead, or shoulder 12, for holding engagement with a part of the head, as will be pointed out presently. This end wall 10 also has an upstanding axially positioned hollow boss 13, provided with a central opening 14, to accommodate a spring closed valve 15. This boss 13, as will be explained in detail hereinafter, frictionally engages a part of the dispensing head.

The spring closed valve 15 includes a tubular housing 16 mounted in said opening 14. The inner end of this housing forms a valve seat against which the valve head, or disk 17, normally is held seated by means of a coil spring 18. A valve stem 19 extends axially through said spring and housing and terminates a short distance above the housing. A cross pin 20 and the flange at the bottom end of the housing 21, hold the spring under compression to normally close the valve. Internal pressure also assists in holding this valve closed.

My invention resides primarily in the means for opening the valve and so forming said means that it can be locked in an inoperative position,

2

such that it cannot be moved to open the valve 15.

Specifically, my dispensing head comprises a cap 22 having a top portion 23 and depending marginal attaching flange 24, which encompasses and grips the bead, or rib 12, on the container end wall 10. A cylindrical body 25 depends axially from said top portion and telescopes over the aforementioned boss 13. If desired, an internal rib 26 or circumferentially spaced projections, 5 may be formed internally of said body for frictional holding engagement with the boss. A discharge tube 27 extends radially from an upper portion of the cylindrical body 25.

The upper end of this cylindrical body 25 is 10 closed partially by means of a generally hemispherical wall 28 which provides a seat for the valve actuator 29. An arcuate slot 30 in said wall 28 accommodates a finger-piece 31 which forms 15 a part of the actuator. This slot extends generally longitudinally, substantially from the juncture of said hemispherical wall 28 and the side wall of the cylindrical body, where it provides a first stop 32, to a point slightly beyond the axis of the body where it provides a second stop 33. These stops limit the extent of movement of the actuator about its axis by engaging 20 a finger-piece 31 on said actuator 29.

This actuator, in the form illustrated, 25 comprises a generally spherical element carrying said finger-piece 31 and seats against the aforementioned hemispherical wall 28 with the neck 34 of the finger-piece positioned in the slot and the head 35 projecting beyond said slot. A flange 36 at one end of said head 35 provides a notch 37 into which the first stop 32 snugly fits when the finger-piece is in position (Fig. 3) to permit closing of the valve under spring pressure. Thus, 30 as is apparent, the actuator may be effectively held against such movement as would open the valve. Shifting of this actuator to the other extreme position, or nearly so, completely disengages it from said stop 32, so that downward pressure and movement in an axial direction results in opening of the valve. If desired, a 35 projecting rib 38 may be formed on the actuator for contact with the valve stem. Such insures adequate space for passage of the contents to the discharge tube 27.

It will also be observed that the internal diameter of the cylindrical body 25 is substantially 40 the same as the actuator. Thus, in assembling the parts, the actuator is passed through said body 25 and positioned as shown in Fig. 3. Preferably, polyethylene, or some material having 45 like characteristics, is used in producing my dis-

3

pensing head, with the exception of the actuator which is formed of some comparatively hard moldable material, such as one of the phenolic resins.

Although I have shown the actuator as being substantially spherical, it is apparent that such shape may be other than spherical. Other modifications may be resorted to within the spirit and scope of the appended claims.

I claim:

1. In a valved dispensing head for a pressure type container, a cylindrical body having one end open, a valve actuator seat within the other end of the body comprising a generally hemispherical wall provided with an arcuate slot, the ends of said slot providing a first stop substantially at the juncture of the seat and side wall of the body and a second stop positioned slightly to one side of the axis of said body, a valve actuator consisting of a generally spherical element engaging said seat, substantially L-shaped fingerpiece carried by said element and extending outwardly through the slot, a spring closed valve openable by bodily movement of the actuator axially of said cylindrical body when the finger-piece is spaced a predetermined distance from the first-named stop, and a discharge tube extending radially outward from and opening at one end to the interior of said body in proximity to said valve actuator.
2. The combination defined in claim 1 in which a projecting rib is formed on said element for engagement with the valve.
3. In a pressure type container, a dispensing valve comprising a tube providing a discharge passageway through a wall of the container and having a valve seat at its inner end, a valve, a stem for the valve extending through said tube, a spring normally holding the valve seated, a valve actuator for opening the valve consisting of an

element arranged at one end of the valve stem and normally positioned to permit closing of said valve under influence of the spring, said actuator being mounted for movement in an arcuate path about an axis extending therethrough normal to the axis of said valve stem and also movable bodily at one end of the path toward and into engagement with said one end of the valve stem to open the valve, and means for positively holding the actuator against said bodily movement when in position to permit closing of the valve.

4. In a pressure type container, a dispensing valve comprising a tube providing a discharge passageway through a wall of the container and having a valve seat at its inner end, a valve, a stem for the valve extending through said tube, a spring normally holding the valve seated, a valve actuator for opening the valve consisting of an element arranged at one end of the valve stem and normally positioned to permit closing of said valve under influence of the spring, said actuator being mounted for movement about an axis extending therethrough normal to the axis of said valve stem to a second position remote from the first named position, said element when in the second position being free for bodily movement toward and into engagement with said one end of the valve stem to open said valve, a finger-piece on said element to facilitate manual movement of the latter and a stop with which said finger-piece is engageable to hold the latter and the actuator against said bodily movement.

5. The combination defined in claim 3 wherein a projecting rib on said element engages the valve stem incident to bodily movement of the element in one direction axially of said valve stem.
